CIRCUIT INTERRUPTER WITH SPEED
CONTROL OF CONTACTRoswell C. Van Sickle, Pittsburgh, Pa., assignor
to Westinghouse Electric Corporation, East
Pittsburgh, Pa., a corporation of Pennsylvania

Application November 6, 1948, Serial No. 58,763

8 Claims. (Cl. 200—82)

1

This invention relates to circuit interrupters and more particularly to circuit interrupters that are operated by compressed gas motors.

Compressed gas motors for operating circuit interrupters develop their maximum power almost immediately after the beginning of the stroke. Because of this, excessive velocity and kinetic energy is developed during the closing stroke which results in excessive slamming and possible damage to the interrupter parts on closing operations. It is an object of the present invention to control the moving parts of a circuit interrupter to reduce the stresses on the parts and to reduce the energy losses due to shock and vibration.

Another object of the invention is to reduce the speed of the moving contacts of a circuit interrupter immediately before the moving contact parts touch the interrupting structure.

Another object of the invention is to increase the effective mass of the moving parts of a circuit interrupter just before the contacts touch on a closing operation to thereby reduce the speed of the moving contact.

Another object of the invention is to provide an inertia device related to the operating mechanism of a circuit interrupter in a manner to reduce the speed of the moving parts of the circuit interrupter just before the contacts touch during a closing operation.

The novel features that are considered characteristic of the invention are set forth in the appended claims. The invention itself, however, both as to structure and operation, together with additional objects and advantages thereof will be best understood from the following detailed description of one embodiment thereof when read in connection with the accompanying drawings:

In said drawings:

Fig. 1 is an elevational view, partly in section and partly schematic, of a circuit interrupter embodying the principles of the invention.

Figs. 2 and 3 are enlarged sectional elevational views of the inertia device taken on lines III—III of Fig. 4 showing the inertia device respectively in the open and closed positions.

Fig. 4 is a front elevational view showing the inertia device and a portion of the circuit interrupter operating mechanism.

Fig. 5 is a graphic illustration of the closing speed of the circuit interrupter lift rod with and without the inertia device.

Referring to Fig. 1 of the drawings, the circuit interrupter, indicated generally at 11, may be of any conventional construction either of the oil break, air break or gas blast type and is oper-

2

ated to closed position by means of a compressed gas operated mechanism indicated generally at 13 (Fig. 1).

The operating mechanism includes a main casting 15 which is formed to provide an operating cylinder 17 closed at its upper end by an integral portion of the main casting 15. The lower end of the cylinder 17 is closed by means of a member 19 suitably secured thereto and provided with a relatively large port 21 which is open to the atmosphere. An operating lever 23 is pivotally mounted at one end on the casting 15 and consists of a pair of spaced parallel levers (only one being shown) connected at one end by a pivot pin 25 to the upper ends of spaced parallel links 27. The lower ends of the links 27 are pivotally supported by means of a pivot pin 29 on ears 31 (only one being shown) formed on the main casting 15. The free ends of the operating levers 23 between them carry a short shaft 33 upon which is mounted a latch roller 35 disposed between the levers 23.

The circuit interrupter 11 is biased to open position by means of an accelerating spring 37 and is connected to the operating mechanism 13 by means of an insulating lift rod 149 (Fig. 1), a lever system indicated generally at 147, a horizontal pull rod 111, a lever system 109 and an operating rod 39 pivotally connected to the operating lever 23 by a pivot pin 40.

In order to hold the interrupter closed, following a closing operation, the operating lever 23 is releasably held in closed position by means of a latch mechanism indicated generally at 61. The latch mechanism comprises a main latch 63 pivotally supported on the main casting 15 by means of a pivot pin 65 and biased to latching position by a spring 67. The latch 63 is adapted to engage the latch roller 35 carried by the operating lever to restrain the operating mechanism and the circuit interrupter in closed position. The main latch 63 is of the slip off type and will not, by itself, hold the operating lever in closed position for which reason there is provided an auxiliary latch 69 which engages and holds the main latch in latching position. The auxiliary latch 69 is pivotally mounted on a pin 71 on the main casting and is biased by means of a spring 73 to latching position.

A holding lever 75 pivoted on the pin 71 and biased by a spring 77 is provided to hold the auxiliary latch 69 in unlatched position when the interrupter mechanism is out of the closed position.

An electromagnetic trip device indicated generally at 83 is provided to actuate the latch

mechanism 61 to effect automatic opening of the interrupter. The trip device comprises a core member 85, an energizing coil 87, a movable armature 89 and a trip rod 91 secured to the armature.

When the trip device 83 is energized, the armature 89 is moved upwardly causing the trip rod 91 to engage the tail 81 of the auxiliary latch 69 moving the latter to unlatching position. This frees the main latch 63 and permits opening movement of the operating rod 39 and the interrupter mechanism.

The breaker operating rod 39 is connected at its upper end through the lever system indicated generally at 109 (Figs. 1 and 4) to the horizontal pull rod 111. The lever system 109 is enclosed in a housing 113 having a clearance opening in the bottom through which the operating rod 39 extends. Secured to the upper end of the operating rod 39 within the housing 113 is a clevis 115, the two arms of which are connected by means of a pivot pin 117 to a pair of reversed bell cranks 119. The bell cranks 119 are mounted for pivotal movement on a pin 121 having one end mounted in a bearing 123 secured to the right side plate (as viewed in Fig. 4) of the housing 113 and the other end supported in a plate 125 secured to the back plate of the housing (Figs. 1 and 4).

Each of the bell cranks 119 comprises a short arm 127 and a long arm 129, each of the arms of the clevis 115 being disposed between the long and short arms of its associated bell crank 119 (see Fig. 4). The lower end of a link 131 is disposed between the free ends of the long arms 129 of the bell cranks 119 and is pivotally connected thereto by means of a pin 133. The upper end of the link 131 is pivotally connected by means of a pin 135 to one arm of a bell crank comprising a pair of bell cranks 137 disposed one on each side of the link 131 and rigidly secured to a rectangular shaft 139. The shaft 139 has reduced ends and is rotatively mounted in bearing plates 141 secured to the inner sides of the side plates of the housing 113 (Fig. 4). The other arm of the bell crank 137 is connected by means of a pivot pin 143 to the horizontal pull rod 111. Thus the vertical movement of the operating rod 39 is transmitted through the lever system 109 to actuate the pull rod 111 to close the interrupter.

The circuit breaker may comprise two or more poles, each pole being disposed in its own separate tank, a fragment of which is shown at 145 (Fig. 1). Each pole of the breaker includes a pair of interrupters 11 but since the interrupters 11 are all alike, only one has been shown. The horizontal pull rod 111 extends to each of the poles to effect simultaneous operation of all of the poles of the breaker. The pull rod 111 is connected through the lever systems (only one of which is shown) indicated generally at 147 (Fig. 1) to the breaker lift rod 149 for each pole for actuating the interrupters 11.

The interrupters 11 may be of any desired type, the preferred type being that disclosed in Patent No. 2,420,883 issued May 20, 1947, to W. M. Leeds and assigned to the assignee of the present invention. Only a brief description of the interrupter will be given herein. Reference may be had to the above noted patent for a more complete understanding of the interrupter.

The interrupters 11 are supported on the inner ends of insulating bushings 41 (only a frag-

ment of one being shown) extending through and supported on the cover of the tank 145. In the closed position the two interrupters 11 are electrically connected together by a conducting cross-bar 43 secured to the lower end of the insulating lift rod 149 and a pair of movable contacts 45 (only one being shown) disposed on the outer ends of the cross-bar 43. Disposed within a pressure generating chamber 47 is a pivoted pressure contact 49 and an intermediate contact 51. The pressure contact 49 is actuated by an insulating operating rod 53. A compression spring 55 biases the operating rod 53 downwardly to effect opening movement of the pressure contact upon opening movement of the cross-bar 43. An adjusting screw 57 and a lock nut 59 therefore, is provided on the lower end of the operating rod 53 to accurately adjust the position of the contact 49 in the closed position.

The lever system 147 is enclosed in a housing 151 (Fig. 1) secured to the top of the tank 145 and comprises an arm 153 having a pivotal connection indicated at 154 with the horizontal pull rod 111 and rigidly secured to a shaft 155 which is pivotally supported in the sides of the housing 151. An arm 157, also rigidly secured to the shaft 155, has its free end connected by means of a link 159 to a lever 161 at a point substantially midway between its ends, the link 159 being pivotally connected by means of a pin 163 to the free end of the arm 157 and by means of a pin 165 to the lever 161. The lever 161 is suspended by means of links 167 and 169 in a manner to impart a straight line vertical movement to the lift rod 149 for opening and closing the interrupter contacts. The lever 167 is pivoted on a fixed pivot pin 171 supported in the sides of the housing 151 and is pivotally connected to the lever 161 by the pivot pin 165. The link 169 is pivoted on a fixed pivot 173 also supported in the sides of the housing 151 and is pivotally connected by means of a pivot pin 175 to one end of the lever 161. The other end of the lever 161 is pivotally connected by means of a pin 177 to the upper end of the lift rod 149.

Downward movement of the operating rod 39 acting through the lever system 109 moves the horizontal pull rod toward the left as viewed in Figure 1. This movement of the pull rod 111 acting through the connection 154 rotates the arm 153, shaft 155 and arm 157 in a counter-clockwise direction and draws the link 159 upwardly. This pulls the lever 161 upwardly and the lever, swinging on the links 167 and 169 draws the lift rod 149 and the cross-bar 43 upwardly to close the contacts.

During the upward or closing movement of the lift rod 149 the cross-bar first picks up the operating rod 53 and moves it upwardly therewith to actuate the pressure contact 49 to the closed position. Thereafter the movable contact 45 engages and moves the intermediate contact 51 into engagement with the pressure contact 49 to close the circuit through the interrupters 11.

The interrupter is adapted to be closed by compressed gas admitted to the cylinder 17 above the operating piston 93. The piston is secured to a piston rod 95 slidable through an air-tight opening in the top of the cylinder. A connector 97 is threaded to the piston rod 95 and to the operating rod 39. The connector 97 is also pivotally connected to the operating lever 23 by a pivot pin 40 thus directly connecting the piston 93 to the operating rod 39 and to the lever 23.

Compressed gas is admitted from an auxiliary

reservoir 99 to the upper end of the cylinder 17 through an inlet passage 101 which is controlled by a main inlet valve 103. The opening operation of the inlet valve 103 is, in turn, controlled by an electromagnetically operated pilot valve 105. The pilot valve 105 is operated by an electromagnet 107 which, when energized, causes opening of the pilot valve 105 to admit compressed gas from the reservoir 99 to operate the main inlet valve 103. Actuation of the inlet valve admits compressed gas to the upper end of the operating cylinder 17 which drives the piston 93 and the operating rod 39 quickly downward to close the interrupter.

When the mechanism is operated to closed position, the latch roller 35 engages the inclined surface of the main latch 63 and moves the latch counterclockwise until the roller passes the nose of the latch. The spring 67 thereupon restores the main latch to latching position.

The operating cylinder is also provided with an exhaust valve (not shown) for quickly reducing the pressure on the working side of the piston to permit high-speed opening of the circuit breaker. The exhaust valve is operated to open position by gas pressure in the cylinder when a pilot valve 108 (Fig. 1) is opened by operation of the trip device 83.

The fluid motor mechanism including the inlet valve and exhaust valve mechanisms is of the type disclosed in Patent No. 2,408,199, issued September 24, 1946 to J. M. Cumming and R. C. Cunningham, and assigned to the assignee of the present invention. For the details of construction of the fluid motor and its inlet and exhaust valve mechanisms reference may be had to the aforementioned patent.

During a closing operation of a compressed gas operated circuit breaker the greatest force of the operating mechanism is required during the latter portion of the closing stroke. Before the moving contact structure picks up the interrupter mechanism during a closing operation the moving contact moves relatively freely and acquires a high velocity. If the moving contact structure picks up the interrupter mechanism while travelling at high speed, severe stresses, excessive slamming of the parts and energy losses will result. This is particularly true in the type of circuit breaker illustrated when the rapidly moving cross-bar 43 engages the interrupter operating rods 53 bearing in mind that there are two interrupters 41 for each pole of a three pole breaker. Consequently, the moving contact structure, while travelling at high speed, must suddenly pick up six interrupter mechanisms.

An important feature of the present invention is the provision of means for reducing the speed of the moving contacts immediately before the moving contacts pick up the interrupter mechanisms. This means comprises an inertia device shown generally at 179 (Figs. 2, 3 and 4). The inertia device includes a mass 181 rigidly mounted by means of bolts 182 between the free ends of a pair of spaced parallel levers 183 and 185. The levers 183 and 185 respectively are pivotally supported in bifurcated support members 187 and 189 on pins 191 and 193. The support member 187 is rigidly secured to the support plate 125 and the member 189 is rigidly secured to the inside surface of the side plate of the housing 113. The levers 183-185 and the mass 181 are connected by means of a toggle comprising a link 195 and an arm 197. The link 195 comprises a pair of links 195 connected to the free end of an arm 197 which

is rigidly secured to the rectangular shaft 139 to which are secured the arms 197 for operating the pull rod 111. The links 195 are disposed one on each side of the arm 197 and are pivotally connected thereto by means of a pin 199. The links 195 are pivotally connected to the levers 183-185 adjacent the mass 181 by means of a pin 201 which extends through both levers 183-185 and both links 195. A spacer 203 is provided to space the links 195 apart and the links are properly spaced from the levers 183-185 by means of spacers 205.

During a closing operation the shaft 139 is rotated counterclockwise from the position shown in Figs. 1 and 2 to the position in which is appears in Fig. 3. During the early part of the closing stroke the levers 183-185 and the mass 181 rotate clockwise about the pivots 191-193 at a relatively low speed and impose a negligible restraining force on the operating mechanism. The pivot pin 199, during its counterclockwise rotation from the Fig. 2 position, approaches a line indicated at A drawn through the pivot 191-193 and the center of the shaft 139 as the moving contact nears the stationary contact. At this time the operating mechanism, acting through a very small moment arm, suddenly attempts to move the inertia device at high speed. The energy required to accelerate the speed of the inertia device causes a substantial reduction in the closing speed of the breaker mechanism including the breaker lift rod 149 just before the moving contact engages the interrupter mechanism.

The energy of the closing means is not dissipated by the inertia device, but is stored therein and, after the moving contacts are brought smoothly into engagement with the stationary contacts, most of the energy is returned to the operating mechanism to assist in the final closing movement thereof. During a closing operation, the moment arm with which the arm 197 drives the inertia member 179 decreases until approximately the time the pin 199 crosses the line A (Fig. 3). Consequently the mechanism accelerates the speed of movement of the inertia member and the inertia member absorbs energy from the mechanism up to this point. Thereafter the moment arm increases and the speed of the mass 179 is reduced hence, the energy absorbed by the inertia device up to this point causes it to attempt to move faster than the mechanism, thus exerting a pull on the mechanism assisting the mechanism in the closing operation until the pin 199 crosses the line B (Fig. 3). At this point in the operation the toggle 195-197 is fully extended and the inertia member 179 has reached its point of greatest clockwise travel which is indicated at 183' in Fig. 3. Thereafter during the closing operation the influence of the inertia member on the mechanism is negligible.

The closing speed of the circuit breaker, both with and without the inertia device, is graphically illustrated in Fig. 5, in which the curve C represents the closing speed without the inertia device and curve D illustrates the closing speed of the circuit breaker controlled by the inertia device. Curve D shows that by use of this invention the speed of the moving parts of the circuit breaker is substantially reduced (about 50%) just before the contacts engage and that the inertia device then returns a large part of the energy to the mechanism to assist in the final closing operation.

While the inertia device has been shown as applied to the shaft 139, it will be obvious that it could be applied to the shaft 155 (Fig. 1) or the same results could be attained by applying an inertia device of the type described and shown to the mechanism 147 for each pole of the breaker.

The inertia device is picked up gradually and applies its greatest restraining force just prior to contact engagement thus reducing stresses on the interrupter mechanism, lift rod and operating mechanism and also reduces energy losses due to shock and vibration.

The amount of deceleration may be varied by substituting a mass of greater or lesser weight for the mass 181. Also the time during a closing operation at which the inertia device retards the closing speed of the mechanism and the lift rod may be varied by varying the position of the arm 191 circumferentially about the shaft 139.

Having described the invention in accordance with the patent statutes, it is to be understood that various changes and modifications may be made in the structural details thereof without departing from the essential features of the invention.

I claim as my invention:

1. A circuit interrupter having a series of connected parts including a shaft which are moved during the entire movement of the interrupter to closed position, power operated means for moving said series of parts to close the interrupter, a pivoted mass, an arm on said shaft, and connecting means at all times connecting said mass to said arm and having its line of action movable over center, said parts and said mass being constructed and arranged in a manner whereby said over center movement causes said mass to absorb a part of the energy of the moving parts at a predetermined time during a closing movement.

2. A circuit interrupter having relatively movable contact means, power operated operating mechanism for closing the circuit interrupter, a shaft rotatable by said operating mechanism to close said circuit interrupter, an arm on said shaft, a pivoted inertia member, and a link connecting said inertia member at a point near its free end to said arm, said link and said arm forming a toggle movable over center upon closing operation of said operating mechanism to cause said inertia member to first retard closing movement of said shaft and then to apply a force to said shaft urging said shaft in closing direction.

3. A circuit interrupter comprising stationary and movable contact means, a series of parts including a shaft operable to close the interrupter, power operated means for moving said parts and said shaft, an arm on said shaft, an unbalanced mass, a pivot for supporting said unbalanced mass, a link connecting said mass to said arm for movement therewith having its line of action movable over center, and said pivot being disposed adjacent the path of movement of said arm so that said over center movement causes said mass to retard movement of said parts for a predetermined time during a closing operation.

4. A circuit interrupter having a series of parts which are moved together during movement of the interrupter to closed position, an inertia member, and an over-center linkage connecting

said inertia member to one of said parts for operating said inertia member, said linkage and said part forming a toggle movable over center during a closing operation so that the mass of said inertia member is applied to said moving parts in a manner to increase the effective mass of said moving parts at a predetermined time during the closing movement to retard the closing movement of said parts.

5. A circuit interrupter comprising stationary and movable contact means, operating mechanism therefor including a series of parts which are moved together to effect closing movement of said movable contact means, a pivoted inertia member, connecting means pivotally connecting said inertia member to a part of said operating mechanism for movement therewith at all times, said connecting means and said part forming a toggle movable over center to first cause said inertia member to retard opening movement of said mechanism just before the contact means engage and then apply a force to assist said operating mechanism during the latter portion of the closing movement.

6. A circuit interrupter having a series of parts which are moved together during movement of the interrupter to closed position, a pivoted inertia member, a linkage connecting said inertia member to one of said parts for operating said inertia member, said linkage and said part forming a toggle movable over center during a closing operation to cause said inertia member to absorb a portion of the kinetic energy of said moving parts at a predetermined time during the closing movement, and said linkage being constructed and arranged to then restore a portion of the energy to said moving parts.

7. A circuit interrupter having a series of parts including a shaft rotatable to close said interrupter, an arm on said shaft, an unbalanced mass, a pivot supporting said unbalanced mass, a linkage connecting said unbalanced mass to said arm, said arm being movable over center relative to said pivot at a predetermined time during the closing operation to cause the mass to retard closing movement of said parts and said shaft.

8. A circuit interrupter having a series of parts including a shaft operable to close said interrupter, an arm on said shaft, an energy storing device comprising a mass pivoted on a fixed pivot, a linkage connecting said energy storing device to said arm for movement therewith at all times, said mass, said pivot and said linkage forming a toggle movable over center to cause said mass at a predetermined time during a closing operation to absorb energy from said parts to thereby retard closing movement of said parts and then later during the closing operation return stored energy to said parts to assist said parts in the closing operation.
